UNITED STATES PATENT OFFICE.

WILLIAM MACGLASHAN, OF DETROIT, MICHIGAN, ASSIGNOR TO THE STUDEBAKER CORPORATION, A CORPORATION OF NEW JERSEY.

AUTOMOBILE-HOOD-SECURING MEANS.

1,183,216.

Specification of Letters Patent. Patented May 16, 1916.

Application filed April 21, 1915. Serial No. 22,745.

To all whom it may concern:

Be it known that I, WILLIAM MACGLASHAN, a citizen of the United States of America, and resident of the city of Detroit, 5 county of Wayne, and State of Michigan, have invented certain new and useful Improvements in Automobile-Hood-Securing Means, of which the following is a specification.

10 This invention is a fastening device adapted more particularly as a hood fastener for motor vehicles.

The purpose of the invention is to fasten the bonnet or hood of a motor vehicle in 15 position in such manner as to minimize vibration of the hood against adjoining structures, and to accomplish such object in a simple and economical manner.

It has heretofore been proposed to mount 20 resilient catches on the frame to engage the hood and hold the same down by a pressure in a vertical direction, that is to say, operating in a plane parallel with the sides of the hood. Such devices do not prevent the 25 vibration of the hood against the cowl and radiator which occurs when a car is driven over an ordinary road.

This invention overcomes the annoying rattling of the hood in its contacting parts 30 and retains the hood in its closed position by mounting a resilient element to engage the hood whereby a pressure both downwardly and parallel to the hood is exerted, and at the same time the element exerts 35 pressure at an angle to the hood. Where resilient elements are employed on each side of the hood, the direction of the pressure exerted on both sides of the hood converges at a point below the radiator, thereby securing 40 the hood firmly in position.

The invention contemplates the provision of a resilient element loosely mounted for inclined movement in a suitable part of the hood-supporting frame, said element having 45 a retaining rear portion to engage a part of the hood and draw the same downwardly and inwardly, and a forwardly directed actuating portion serving as means to retract the element, whereby the retaining rear portion may be readily drawn upwardly and outwardly away from the hood when it is desired to elevate the hood from the frame.

An embodiment of the invention is set 50 forth in the accompanying drawings, but

it is to be understood that the construction 60 therein disclosed is for the purpose of illustration only and not as defining the limits of the invention.

In the drawings:

Figure 1 is a side elevation showing a plurality of fastening elements engaging a bonnet or hood of an automobile. Fig. 2 is a vertical sectional view disclosing the fastening element in enlarged form, and the 65 means of mounting the same to engage a retaining part of the hood. Fig. 3 and Fig. 4 illustrate an alternate form of fastening device, Fig. 3 being a vertical section and Fig. 4 a detail in elevation.

In the construction disclosed in the accompanying drawings, the bonnet or hood 1 may be of the usual or conventional form and may be of any suitable material, such as sheet metal, having the usual rolled lower 70 portion 2 terminating in a stiffening bead 3 at the sides thereof. It is obvious that this bead may extend along each side of the hood, and that the fastening devices may be positioned on each side of the hood, although 75 only one side is illustrated in the drawings.

In Fig. 2 the bonnet is shown resting upon a ledge 4 having an angular portion 5, said ledge being formed at the rear of the usual radiator and also at the front of the cowl, 80 (not shown). These ledges are shown provided with suitable cushioning material, which may be in the form of leather or suitable resilient strips indicated at 6, and which 85 may be laced through the angular portion 90 5 of the ledge 4, as illustrated.

The fastening device to engage the hood, 95 may be mounted on any suitable portion of the frame, but in the drawings there is shown a side rail of a frame, at 7, which 100 supports a splash apron indicated at 8, and mounted above the splash apron to extend under the edge of the hood 1 in a closed position, may be a suitable ornamental strip of metal indicated at 9. This strip is shown 105 angular and curved in form, and is preferably provided with an aperture 10 having a depressed portion 11 which serves as a seat for the plunger on the stem of the fastening element, and also for the resilient means to 110 engage the fastening element. The members 7, 8 and 9 may be secured by any suitable means, such as the bolts 12.

The fastening element illustrated as the preferred embodiment of the invention, is 110

shown comprising a stem 13 having an abutment 14 at one end thereof against which may be mounted a collar 15, with any suitable means such as a cotter pin 16 to retain the collar 15 on the stem 13. Near the upper end of the stem 13 is shown a stop member 17 which is adapted to be seated against the curved and depressed portion 11 surrounding the aperture 10 in the strip 9. Above the stop member 17 the device is formed with an actuating element, which may be of any desired shape. In the drawing, however, this actuating element is shown as a hook-shaped member 18 which extends rearwardly out of alignment with the stem 13 to an enlarged thickened portion 19, to thereby form a recess 20 for the reception of the bead 3 of the hood 1. From the thickened portion 19 the actuating member extends upwardly, thence forwardly, and outwardly, terminating at a substantially pointed end 21 slightly beyond the plane of the stem 13. It will be observed, therefore, that the retaining recess 20 for the bead 3, is out of alignment with the stem 13, and that the outer edge 22 of the thickened portion 19 which forms the recess 20, will serve to engage the bead 3 in a downward direction when a resilient element acts against the collar 15 of the stem 13. One form of resilient means is disclosed in the helical spring 23, through which extends the stem 13, one end of the spring engaging the collar 15, while the other end is shown enlarged as at 24 to extend around and be seated against the depressed curved portion 11 of the strip 9. The action of this spring, and of the enlarged portion thereof seated around the portion 11, serves to mount the retaining member at an angle with relation to its supporting means. Moreover, the depressed portion 11 is preferably formed in a portion of the plate 9 which is at an angle to the remaining parts of the plate; said angle may be for example, at forty-five degrees with relation to the perpendicular and horizontal plates adjacent to the plate 9. By this means the fastening element is maintained normally at an angle to its supporting elements and to the movable hood.

In operation the hood may be lowered as usual until its sides 1 bind against the cushioning material 6 of the ledges 4, whereupon the actuating part 18 may be released to enable the resilient means 23 to bring the parts 20 and 22 into engagement with the ledge 3. The resilient means will then operate to exert a downward pressure upon the hood, parallel with the sides thereof, and also a pressure at an angle to the hood, by reason of the positioning of the angular pressure being upon both sides of the hood converging at a point substantially below the radiator. This action binds the hood against the ledges 4 which are mounted adjacent the cowl and

the radiator whereby vibration is minimized and the hood retained by elastic means in contact with the cushioning strips 6.

In Figs. 3 and 4 I have shown an alternate form of construction of the fastening element, the difference in construction being as follows: The aperture 10^a is formed to serve the purpose of a socket, the hood is provided with hooks as 25 secured thereto, the resilient fastening member comprises a stem as 26 carrying at one end a ball 27, adapted to coöperate with a socket 10^a and having a head 28 secured to the end opposite the ball. 29 is a cylindrical casing, one end thereof being hemispherical as at 30 and having an aperture through the longitudinal center thereof as at 31 to receive the stem 26. The helical spring 32 is interposed between head 28 and the end of the casing 29 and surrounding the stem 26. The finger piece 33 as shown in Fig. 4 is secured to the opposite end of the cylindrical member 29. The operation of this alternate construction is the same as that previously described in all essential particulars.

Having thus described my invention, what I claim as new and desire to secure by Letters Patent is:

1. The combination with a fixed support and a movable element adapted to be secured thereto, of a fastening element having means to engage said movable element to draw the same downwardly and inwardly toward the fixed support.

2. The combination with a fixed support and a movable element coöperating therewith, of a fastening element mounted to engage the movable element to draw the same downwardly and at an angle to the plane of the movable element.

3. The combination with a fixed support and a movable element adapted to be secured thereto, of a plurality of fastening elements angularly mounted on the fixed support to engage opposite sides of the movable element to exert pressure on the sides in a downwardly and inwardly direction.

4. The combination with a fixed support and a movable hood coöperating therewith, of a fastening element adapted to be loosely mounted to extend through the fixed support and provided with means to engage the hood to exert a pressure downwardly substantially parallel to the hood and also at an angle to the hood.

5. The combination with a fixed support and a movable hood having a retaining member secured thereto, of a fastening element comprising a stem adapted to be loosely mounted in the fixed support, an actuating member at one end of, and out of alignment with, the stem to form means to engage the retaining member of the hood, and resilient means to engage the fixed support and the stem to position said stem at an angle

to the plane of the hood and the fixed support, and to exert pressure on the hood through its retaining members.

6. The combination with a fixed support, 5 a movable hood having a protruding retaining member, of a fastening element angularly mounted on the fixed support comprising an offset member to engage the retaining member of the hood, and resilient means to cause said offset member to exert pressure downwardly on the hood and also at an angle to the hood to cause the latter to impinge against the fixed support.

7. A device of the class described, including a fixed support having an aperture with an inturned wall to provide a seat, and a spring-actuated fastening element mounted for universal movement on the fixed support, said fastening element comprising a stem 20 adapted to extend through said aperture and having an abutment near one end thereof and a stop near the other end to engage said seat, and a helical spring for said stem to engage said abutment and to have an enlarged portion thereof to engage the in-turned wall of the seat.

8. A fastening element comprising a stem adapted to be loosely mounted in a support and provided with an abutment, an actuating member as an extension of said stem and having a portion thereof out of alignment with the stem to form a recessed offset, and a resilient element interposed between the stem abutment and the support.

9. A hood adapted to inclose the engine of an automobile, in combination with flanges suitably mounted to support the hood at the edges thereof, elastic means interposed between the ends of the hood and 40 points on the frame of the automobile which points are in a plane parallel with the longitudinal axis of the hood, below the ends of hood, and equi-distant therefrom, said points being also nearer together than the 45 ends of the hood.

10. A device of the class described em-

bodying an automobile hood, and a fixed support for said hood, in combination with means for binding the hood around its support and simultaneously impelling the free 50 edges of the sides of the hood toward each other.

11. A hood adapted to inclose the engine of an automobile, in combination with flanges suitably mounted to support the hood 55 at the edges thereof, with elastic means interposed between the ends of the hood and points on the frame of the automobile which points are in a plane parallel with the longitudinal axis of the hood, below the ends of 60 hood, and equi-distant therefrom, said points being also nearer together than the ends of the hood, such elastic connection being mounted at one end to said frame by a ball and socket connection and at the other end 65 to the hood by a hook connection adapted to coöperate with hook engaging means carried by the ends of the hood.

12. A device of the class described embodying an automobile hood, a fixed support 70 for said hood, and cushioning means on said support, in combination with means for binding the hood around its support and simultaneously impelling the free edges of 75 the sides of the hood toward each other.

13. The combination, with a fixed support cushioning means on said support, of a removable hood having a protruding retaining member, a fastening element, angularly mounted on the fixed support, comprising 80 an off-set member to engage the retaining member of the hood, and spring-actuated means to cause said off-set member to exert pressure downwardly on the hood and also at an angle to the hood to force the latter 85 against the fixed support.

Signed at Detroit, Michigan, by me this 15th day of April 1915.

WILLIAM MACGLASHAN.
